UNITED STATES PATENT OFFICE.

JOSEPH S. CORTELYOU, OF BROOKLYN, NEW YORK.

INTERNAL-COMBUSTION ENGINE.

980,494.

Specification of Letters Patent. Patented Jan. 3, 1911.

Application filed May 19, 1896. Serial No. 317,671.

To all whom it may concern:

Be it known that I, JOSEPH S. CORTELYOU, a citizen of the United States of America, and a resident of the borough of Brooklyn, 5 in the county of Kings and State of New York, have invented certain new and useful Improvements in Internal-Combustion Engines, of which the following is a specification.

10 This invention relates to internal combustion engines, and it has particular reference to the type known as the two-cycle engine, wherein a power stroke is provided for every revolution of the crank-shaft.

15 The object of my invention is to provide a two-cycle engine of improved design; and, to this end, the invention consists in the constructions and combinations hereinafter described and claimed.

20 While I have illustrated my invention as applied to a four-cylinder vertical engine, it is obvious that I may equally well use a single pair of cylinders, or other number; also that the cylinders may be placed horizontally in pairs or opposed.

25 In the drawings accompanying this application, Figure 1 is a top plan view of an engine, partly in horizontal section on the line 1—1 of Fig. 2. Fig. 2 is a side elevation partly in vertical section on the line 2—2 of Fig. 1. Fig. 3 is a sectional elevation on the line 3—3 of Fig. 2. Fig. 4 is a partial elevation, enlarged, of the throttling device. Fig. 5 is a horizontal section on the line 5—5 of Fig. 4. Fig. 6 is a vertical section on the line 6—6 of Fig. 5. Fig. 7 is a vertical section on the line 7—7 of Fig. 5. Fig. 8 is a vertical section on the line 8—8 of Fig. 5.

30 As premised, I have illustrated in the drawing, as an example, a 4-cylinder engine, Fig. 2 showing a pair of said cylinders in elevation, and the other pair in vertical section. The members of each pair of cylinders are indicated, respectively, by the letters *a a'*, and are each provided with a concentric enlargement *b b'*, respectively, extending beyond the ends of the cylinders *a a'*, respectively. The enlargements *b b'*, at their lower ends unite with the upper portion *c* 35 of the crank-case, the lower portion *c'* of said crank-case being removable. Because said crank-case is not required to hold compression, its joint need not be packed, and it may be suitably ventilated to provide the

admission of fresh air to cool the lower part 55 of the pistons and cylinders. The pistons, as *d d'*, working in the cylinders, are of the trunk type, and of a length proportionate to that of the cylinders. The connecting rods 60 *e e'*, are pivoted in the pistons at intermediate points of their length, and connect with the crank-shafts through the usual wrist-pins *f f'*. It will be noted that the rear ends of the pistons, on their power stroke, extend beyond the cylinder parts *a a'*, and 65 that said pistons have radial enlargements *g g'*, respectively, which reach out to the concentric enlargements *b b'*, respectively (forming therewith the annular compression chambers *h h'* respectively). As the piston 70 *d* is provided with piston-rings *d² d³*, so may the enlargements *g g'* be provided with piston-rings *d⁴*. The compression chamber *h* communicates, through a passage *i*, with cylinder *a'*, while the compression chamber 75 *h'* communicates, through a passage *i'*, with cylinder *a*.

80 A throttling device, as *j*, is interposed in the passages *i i'*, and a puppet-valve or balanced valve, as *k k'*, is placed in each cylinder head, being held to its seat by a spring *l l'*, whereby, when the pressure in a power cylinder equals or exceeds the pressure in the compression chamber which supplies its charges, said valve remains closed, but when 85 the pressure in the compression chamber is greater than the pressure in the power cylinder which said chamber supplies, then said valve opens to admit a new charge.

89 A number of exhaust ports *m m'*, are arranged in a transverse plane around each cylinder in manner to be uncovered by the piston at the end of its power stroke. Said ports communicate with a concentric chamber *n n'*, exterior thereto, which is provided 95 with one or more outlets *o o'*.

90 The compression chambers *h h'*, are each provided with an inlet port *p p'*, which ports are adapted to become operative with respect to their particular compression chambers 100 as included in or excluded from said compression chambers through the actions of the respective piston-enlargements *g g'*.

105 The throttling device *j* consists of a cylinder having end closures *j' j'*, and a central dividing diaphragm *j²*, a shaft *j³*, being journaled in said closures *j' j'*, and rotatably filling a central aperture in the diaphragm.

Said shaft j^3 is provided with a crank j^4 or other device by which it may be turned in the throttling operation. By means of diaphragm j^2 the cylinder is divided into two chambers, j^5 , j^6 , which respectively contain oscillating valve members j^7 , j^8 , that are mounted on and adapted to be turned by the shaft j^3 . The valve member j^7 is provided with the oppositely disposed wings j^9 , j^{10} , which are concentric with and adapted to be oscillated in contact with the circular wall of chamber j^5 , and, in their movement, to cover to suitable degrees angularly disposed ports j^{10} , j^{11} , in said circular wall. 15 Similarly the valve member j^8 is provided with wings j^{12} , j^{13} , adapted to cover to suitable degrees angularly disposed ports j^{13} , j^{14} , in the circular wall of chamber j^6 . Thus the chamber j^5 , by its ports j^{10} , j^{11} , under the control of valve j^7 , admits gaseous charges, emanating from compression chamber h' , to combustion chamber a , and, similarly, the chamber j^6 , by its ports j^{13} , j^{14} , under the control of valve j^8 , admits gaseous charges, emanating from compression chamber h , to combustion chamber a' .

In the operation of a pair of cylinders containing my improvements the cycle is as follows: The piston d in a cylinder a , 30 Fig. 2, is at the limit of its compression stroke and ready to commence its power stroke. The combustible charge, upon being ignited, as by a spark plug located in the orifice q (see Fig. 3), impels said piston on its out-stroke and the burned gases escape through the exhaust ports m toward the end of said power stroke. During this out-stroke the piston enlargement g creates a partial vacuum in the initial compression chamber 35 h . In Fig. 2, the piston d' , in cylinder a' , is at the end of its out-stroke, the ports m' , being shown fully opened and the piston enlargement g' , shown as having passed the inlet p' . As said enlargement g' passed the inlet p' , opening the latter, the partial vacuum that had been created in the initial compression chamber h' , was supplied with a charge from the carburetor or other source of supply, as is obvious. The in-stroke of 40 piston d' , in cylinder a' , now first closes the exhaust ports m' , and the enlargement g' at about the same time closes the inlet p' , with respect to the concentric chamber b' . The burned gases having exhausted through 45 the ports at the end of the out-stroke, the pressure in cylinder a' , was thereby relieved, and during said out-stroke the gaseous charge in initial compression chamber h was being compressed through the concur- 50 rent in-stroke of enlargement g operating in enlargement b , this increased pressure being directed through valve j , and passage i against the rear surface of valve k' , in cylinder a' . Hence, with the lowering of the

pressure in cylinder a' , consequent upon the escape of its burned products, the valve k' , in said cylinder a' , opened under the excess of pressure exerted by the new charge, and such opening occurred before the closing of exhaust ports m' , in cylinder a' , by the in-stroke of the piston, whereby the volume and pressure of the in-coming new charge in cylinder a' , expelled any remaining burned gases, thereby thoroughly scavenging the cylinder. Immediately the piston in cylinder a' has closed the exhaust ports m' upon its in-stroke said piston commences its operation of compressing the new charge that has been admitted, the valve k' remaining open until the pressure set up in cylinder a' by the piston is greater than the pressure of initial compression chamber h , when the valve k' closes, the remaining portion of the piston in-stroke serving to compress the contained new charge to the desired point 85 for firing. It is of course understood that the increase in pressure to close the valve k' occurs immediately the exhaust ports are closed. Thus, each cylinder of the pair receives its explosive charge from an initial 90 compression chamber forming a part of the other cylinder, and having working therein an enlargement of the piston of said other cylinder. Furthermore the pressure in the initial compression chamber of one cylinder 95 is directed against the inlet valve for the power chamber of the other cylinder, said valve being located at a point distant from the exhaust ports of said other cylinder. It will be realized that an operation is hereby 100 set up whereby the force of exploded and expanding gases in one cylinder of a pair compresses a new charge for itself in the other cylinder of the pair, and whereby such concurrent compression of its new charge 105 in said other cylinder serves to aid in exhausting and scavenging its burned gases at the end of its out-stroke, and to recharge it. The great length of connecting rod, as e , and the widely separated piston 110 rings on the elongated piston, serve to reduce the effects of angular force of the piston stroke with respect to frictional wear in its cylinder, as is obvious.

No system of cooling the cylinders has 115 been shown or described, but it is of course understood that my improved engine may be equipped with any known means for dissipating its excess of heat.

While I have described and illustrated my 120 invention particularly with reference to the employment of one or more pairs of cylinders, each cylinder of a pair having a combustion chamber, and a compression chamber operating with the other cylinder of the 125 pair, I do not limit myself to this arrangement, as I may in a multi-cylinder engine use the compression of any one cylinder to

provide the charge for any other one of the cylinders, the specific arrangement depending upon the number of cylinders in the engine.

5 It will be noted that the arrangement of my improved engine is such that the incoming charge enters the cylinder at a point remote from the exhaust ports, and the inlet valve is so placed that the direction of flow 10 of the incoming charge coincides with the direction of flow of the burned gases in their discharge. The cylinder head and inlet valve are so formed and arranged that the incoming charge travels downwardly in 15 manner of a column, while the formation and arrangement of the exhaust ports are of such character that the burned gases leave the cylinder in the manner of a solid column, whereby any tendency of the new 20 charge to mix with the burned gases, to form whirlpools, or to leave any of its volume within the cylinder, is absolutely avoided.

Instead of the single valve as indicated in the drawings, I may use a plurality of inlet valves to assist in the function of admitting the new charge in such manner that it may descend the cylinder in column-like formation. Thus the new charge carries before it the burned gases and thoroughly 25

scavenges the cylinder by impelling said 30 burned gases through the exhaust ports.

I claim:

In an internal combustion engine of the two cycle type, cylinders of two diameters and corresponding pistons working therein, 35 so arranged that the combustion chamber is formed in the smaller bore of each cylinder and the initial compression chamber in the larger bore, said initial compression chamber being adapted to receive the air and fuel 40 for each new charge for the combustion chamber, individual conduits connecting the initial compression chamber of one cylinder with the combustion chamber of another cylinder, said cylinders having their exhaust 45 ports disposed circumferentially around the cylinders at or near the end of the stroke to be uncovered by the pistons in their movement, and their intakes centrally through the cylinder heads, so disposed as to cause 50 the initially compressed charge to enter and travel longitudinally in the cylinder.

Signed at New York this 20th day of April 1906.

JOSEPH S. CORTELYOU.
